Richard B. Devan..

ATTORNEY.

UNITED STATES PATENT OFFICE.

LAWRENCE R. HOWARD, OF CHANDLER, ARIZONA.

WICK.

Application filed April 27, 1920, Serial No. 377,109. Renewed June 21, 1923.

To all whom it may concern:

Be it known that I, LAWRENCE R. HOWARD, a citizen of the United States, residing at Chandler, in the county of Maricopa and State of Arizona, have invented certain new and useful Improvements in Wicks, of which the following is a specification.

This invention relates to tubular wicks such as are used in connection with oil 10 stoves for cooking purposes and it aims to provide a suitable top for the wick which may be removed when burnt out and replaced by a new top.

A further object is to eliminate the necessity for replacing the wick as a whole when the exposed portion requires renewal and it accomplishes this by the provision of a separable and renewable wick top which may be easily and readily attached 20 to the wick carrier.

A further object contemplated by the provision of this invention is to remove the disagreeable features associated with the task of removing an oil soaked wick when 25 replacing it by a new one by the simple expedient of doing away with the necessity of removing the wick at all, it being possible by means of the improved wick forming the embodiment of this invention to leave the 30 wick in the oil while fitting it with a new wick top or burner portion.

With the above and other objects in view, the invention may be said generally to reside in the details of construction, combination and arrangement of parts as will be 35 hereinafter pointed out, reference being had to the accompanying drawings, wherein

Figure 1 is a side elevation of an improved wick constructed in accordance with the invention.

Figure 2 is a vertical central section through the wick.

Figure 3 is a section taken on a horizontal plane through the wick carrier and the removable top.

Figure 4 is a bottom plan of the removable top and

Figure 5 is a fragmentary, sectional view disclosing the manner of connecting the top to the carrier.

Referring now to the several views in the drawings, the numeral 1 indicates a wick of a character usually employed for burners of this type and as shown is of tubular form 55 split adjacent its lower end to permit the

wick to spread out at its bottom when inserted in the reservoir or oil font of the stove with which the wick is used. Embracing the outside adjacent its upper portion is a metallic carrier 2 which may be riveted or otherwise fastened to the wick in any desirable manner. This carrier is provided with a plurality of openings into which the teeth of the wick raiser are adapted to engage for the purpose of raising or lowering the wick upon the wick tube of the oil reservoir. Ordinarily the wick will project slightly above the carrier to provide an exposed portion for lighting purposes, the oil being absorbed by the wick and conducted to the exposed portion by capillary attraction. In the present invention however, the top of the wick is adapted to be cut even with the top edge of the carrier to provide an even surface for a purpose to be herein-after pointed out.

The removable top for the wick comprises an annular band 4 which is adapted to slidably fit over the upper edge of the wick carrier 3 as shown to advantage in Figure 2 of the drawings.

Spaced inwardly of this band and concentrically arranged with respect thereto is a second band or ring member 5 of narrow width which is adapted to be fastened to band 4 by means of rivets or bolts 6. Between this inner and outer band is arranged a short tubular wick element 7 which extends slightly above the top of the member 4 as shown. This wick 7 is adapted to provide a continuation of the lower wick 1 and forms the top or burning portion for the wick. The lower end of top wick 7 which lies flush with the lower edge of the ring member 5, terminates inwardly of the open end 8 of the removable top so that when the latter is slipped onto the end of the wick carrier 3, the meeting edges of the upper and lower wick members will be substantially enclosed by the surrounding band 4. At suitable points the lower end 8 of the band is provided with inwardly depressed portions forming knobs 9 adapted for sliding engagement with the locking groove 10 opening inwardly from the upper edge of the wick carrier 2. It will thus be seen that after the removable top has been slipped over the end of the wick carrier so that the knobs 9 pass downwardly in the vertically disposed branch of the angle slot 110.

105

10 a turning of the top to one side will cause the knobs to move in the right angular branches of the groove as shown to advantage in Figure 1 of the drawings, whereby 5 the top will be removably locked in place upon the carrier.

In operation, this wick could be used in the same places and for the same purposes for which similar wicks of this character 10 are used, the improvement consisting in the fact that the wick may be provided with a new top whenever required, it being merely necessary to remove the old and used top by turning the band to disengage the knob 15 9 from the locking slot thus permitting the top to be removed as a whole and a new one substituted therefor. In this construction, attention is called to the fact that in a wick 20 of this type the removable top is entirely separate and distinct from the wick 1 and the carrier so that the burner may be said generally to consist of two wick carriers adapted to be connected so that their respective wicks meet to join and provide a 25 single continuous wick, the upper portion of which is replaceable. It is thus possible to provide two or more removable wick tops which are interchangeable or replaceable whenever required thus enabling a single 30 bottom wick to last for a considerable period of time since it is only the upper or removable top wick that is ignited and burned.

Having thus described my invention what

I claim as new and desire to secure by Letters Patent is:—

1. An article of manufacture comprising a bottom wick, a wick carrier comprising a tubular band therefor having locking slots, a burner wick, a band connected to the burner wick and depending therebelow, the said depending portion being adapted to embrace the upper edge of the said wick carrier and having projections formed therein for engaging the locking slot of the latter.

2. An article of manufacture comprising a tubular bottom wick, a tubular wick carrier comprising a tubular band therefor having locking slots, a burner wick, an angular band embracing the burner wick and depending therebelow, the said depending portion being adapted to embrace the upper edge of the said wick carrier and having projections formed therein for engaging the locking slot of the latter, said tubular band extending well down over the top of the bottom wick and being provided with a multiplicity of perforations therein, and a second band bowed inwardly of the tubular wick and connected therethrough to the other or outer band.

In testimony whereof I affix my signature in presence of two witnesses.

LAWRENCE R. HOWARD.
